(57) **CLAIM**

We claim the ornamental design for a portable information handling system with detachable gaming controllers, as shown and described.

DESCRIPTION

FIG. 1 is a front perspective view of the of the portable information handling system with detachable gaming controllers comprising the present invention;
FIG. 2 is a front elevation view thereof;
FIG. 3 is a rear elevation view thereof;
FIG. 4 is a right side view thereof;
FIG. 5 is a left side view thereof;
FIG. 6 is a top view thereof; and
FIG. 7 is a bottom view thereof;
FIG. 8 is a rear perspective view thereof;
FIG. 9 is a front perspective view thereof having the gaming controllers detached from the portable information handling system and attached to a bridge;
FIG. 10 is a front elevation view thereof;
FIG. 11 is a rear elevation view thereof;
FIG. 12 is a right side view thereof;
FIG. 13 is a left side view thereof;
FIG. 14 is a top view thereof;
FIG. 15 is a bottom view thereof;
(Continued)

FIG. 16 is a rear perspective view thereof; and, FIG. 17 is front perspective exploded view thereof depicting the game controllers detached from the information handling system and bridge. Broken lines depict portions of the article that form no part of the claimed design.
